UNITED STATES PATENT OFFICE.

MAX BROWN, OF NEW YORK, N. Y., ASSIGNOR TO ROYAL METAL LIGHTING FIXTURE CO. INC., OF NEW YORK, N. Y.

DESIGN FOR A LIGHTING-FIXTURE BRACKET OR ARTICLE OF SIMILAR NATURE.

Application filed June 7, 1928. Serial No. 27,025. Term of patent 3½ years.

To all whom it may concern:

Be it known that I, MAX BROWN, a citizen of the United States, residing at New York city, in the county of Kings and State of New York, have invented a new, original, and ornamental Design for a Lighting Fixture Bracket or Article of Similar Nature, of which the following is a specification; reference being had to the accompanying drawing forming a part thereof.

The figure is an elevational view of a lighting fixture bracket showing my new design.

I claim:

The ornamental design for a lighting fixture bracket or article of similar nature, as shown.

MAX BROWN.
